UNITED STATES PATENT OFFICE

DAVID LEONARD LINDQUIST, OF HARTSDALE, NEW YORK, ASSIGNOR TO OTIS ELEVATOR COMPANY, OF NEW YORK, N. Y., A CORPORATION OF NEW JERSEY

ELEVATOR SYSTEM

Application filed February 26, 1931. Serial No. 518,814.

The present invention relates generally to elevators and refers to an arrangement of the same especially adapted for high buildings or for other installations in which the space available for elevator hatchways is limited.

In the construction of high buildings the most important factor limiting the height to which a building may be erected is that of elevator transportation. Considering the size of the plot on which a building is to be erected and the set-back regulations generally in force, the height is limited by the space required for the elevator hatchways.

10 The set-back regulations, in order to insure adequate light and air for the building and adjacent buildings, usually require that above a certain height the tower cross-sectional area shall not exceed a specified percentage of the plot area. The tower cross section is thus limited in area to a fraction of the size of the plot, for example, to one quarter of the plot area. Thus the major portion of a tower above a certain height 15 may be taken up by elevator hatchways if the usual elevator arrangement for servicing the upper floors, by running the hatchways the entire height of the building with a single elevator car for each hatchway, is employed.

One feature of the invention is to effect an economy in the number of elevator hatchways required for a specified handling capacity.

20 Another feature of this invention is to increase the handling capacity of an elevator hatchway.

Another feature of the invention is to arrange a plurality of elevator cars in the same hatchway so that all cars may travel practically the same distance.

25 A further feature of the invention is to arrange certain hoisting and control connections to each of the elevator cars so that they do not contact the other cars in the hatchway.

Other features and advantages will be hereinafter more fully pointed out and specified.

30 The invention involves the provision of

two or more elevators in a single hatchway each of which is adapted to run from a terminal floor in the lower part of a building to a specified section of floors in the upper part of a building, to serve locally that section in both the up and down directions and to return to its lower terminal floor.

35 For the purpose of illustrating the genus of the invention a concrete embodiment thereof is shown in the accompanying drawings in which,

Figure 1 is a diagrammatic elevation of an electrically controlled elevator apparatus having two cars in the same hatchway as viewed from the front of said hatchway.

40 Figure 2 is a similar view taken from the right hand side of the hatchway as illustrated in Figure 1.

45 Figure 3 is a top plan view, on an enlarged scale, of the apparatus shown in Figures 1 and 2, with certain parts shown only by outline.

50 Figure 4 is a bottom plan view, on an enlarged scale, of the apparatus shown in the above figures, as taken from the lower end 55 of the hatchway pit.

55 Referring to Figures 1 and 2 of the drawings, numeral 10 represents a hatchway having certain of the floor landings leading thereto indicated by legend. A lower and an upper car, designated 11 and 12, respectively, are located in the hatchway 10 and run on a pair of guides 13 (Figs. 3 and 4). In the majority of cases, it is intended to use two 60

ground floor loading levels, the lower car 65 11 using the subway or lower ground level as a terminal floor and the upper car 12 using the street level or upper ground floor for its lower terminal floor. The lower car

70 11 may stop at the street level floor regularly only at certain times, if desired. If it should become necessary or desirable to have the upper car 12 also run to the lower terminal floor, then additional pit depth 75

80 must be provided to allow the lower car 11 to get out of the way of the upper car 12 85 while the latter goes down to the bottom terminal floor.

85 For a clearer understanding of the arrangement of the hoisting and traveling 90

cables for the two cars, reference may also be made to Figure 3 which shows two hoisting machines disposed at different levels above the hatchway 10, upper machine 14 operating the lower car 11 and lower machine 15 operating the upper car 12. Adjacent and parallel to the back wall of the hatchway 10, two long, narrow counterweights 16 and 17 for the lower and upper cars, respectively, are disposed, one on each side of a traveling cable chute 18. These weights may be of lead, if desired. The function of this chute will be explained later. The upper machine 14 is arranged at an angle across the hatchway so that the opposite peripheral margins of the drive sheave 19 of this machine will be disposed, one over the center of counterweight 16 and the other over a point 20 located below machine 15, adjacent the hatchway side wall and at one side of a car guide 13. The hoisting cables 22 for the lower car 11 run from a cable hitch 23 on counterweight 16, over the sheave 19, around a secondary sheave 21 disposed directly below and in the same plane with sheave 19, over the sheave 19 in the same direction as before and thence vertically downward to point 20 where the cables divide. Any desired number of hoisting cables 22 may be employed, two being shown in the drawings. One half of the lower car hoisting cables 22 continue vertically downward to a cable hitch 24 at the bottom of car 11. The other half of the hoisting cables for car 11 run from point 20 under an idler sheave 25, thence across the hatchway and over a second idler sheave 26 to a point 27 diametrically opposite from point 20 with respect to the approximate center of gravity of the elevator car 11. From point 27 cables 22 travel directly downward along the side wall of the hatchway to a second cable hitch 28 which is also located at the bottom of the car diametrically opposite the first named cable hitch 24, with respect to the approximate center of gravity of car 11.

The lower machine 15 for the upper car 12 is also arranged at an angle across the hatchway so that its drive sheave 29 may be allocated in the vertical plane cutting the centers of gravity of both the upper elevator car 12 and its counterweight 17, one peripheral margin of the sheave 29 being arranged directly over the approximate center of gravity of the car. The hoisting cables 30 for the upper car 12 run from a cable hitch 31 on counterweight 17 to a sheave 32 disposed below and in the same plane with sheave 29. Sheave 32 serves both as an idler sheave to effect a change in direction of cables 30 and as a secondary sheave about which the cables 30 pass. Any desired number of cables 30 may be employed, but two being shown in the drawings.

Cables 30 run partially around sheave 32 then make a loop around sheaves 29 and 32 for traction purposes, and from sheave 29 run directly down to a cable hitch 33 on the top of car 12 directly above its approximate center of gravity. The term "approximate center of gravity" of the car has been employed since it may be desirable to fix the exact location of the cable hitches 24, 28 and 33 in accordance with the location of the center of gravity of each car plus an estimated load rather than that of the car alone.

The compensating cables for the lower car 11 are designated 34 and run from a cable hitch 35 on the bottom of the car directly down to and half around a tension sheave 36 then vertically upward to a cable hitch 37 on counterweight 16. Sheave 36 is arranged at such an angle and is of a diameter to carry out the above described compensating cable arrangement.

The compensating cables for the upper car 12 must pass the lower car 11 so are divided and suspended from two points adjacent the top of the car 12 by means of cable hitches 39 and 40 which are fixed to the car and project outwardly beyond its sides. These compensating cables are designated 41 and both run vertically downward to tension sheaves 42, 43 and 44 arranged to guide the cables to points directly below a cable hitch 66 on counterweight 17 to which the cables 41 are fastened. Tension sheaves 36, 42, 43 and 44 may be provided with suitable guide frames 38 as indicated in Figure 4. The arrangement of the sheaves 36, 42, 43 and 44 is clearly illustrated in Figures 1, 2 and 4.

The cable hitches 24 and 28 are located at the bottom of car 11, or at least below the top of the lower car, and the cable hitches 39 and 40 are located at the top of car 12, or at least above the bottom of the upper car so that the two cars may be brought close together without interference between one car and the cable hitches to the other car.

A tape drive is used to operate the selector machine 71 of the lower car 11 and comprises two tapes, 45 and 46, each having one end fixed to a double sheave drum 47 located at approximately the same level as the upper hoisting machine 14 for the lower car 11. The tapes 45 and 46 are oppositely wound on drum 47 so that as tape 46, for example, is unwound from drum 47 by the downward motion of car 11, the drum 47 is rotated in a counterclockwise direction as viewed in Figure 1 and tape 45 winds on the drum 47. Tape 46 runs from the drum 47 over an idler sheave 48 to bring this tape outside the path of travel of elevator car 12 and the second end of this tape is fixed to a bracket 49 which projects outwardly from the top of car 11. Tape 45 leads from the

other side of drum 47, passes over the same side of a second idler sheave 48 as does the tape 45, depends therefrom, at one side of tape 46, to a point in the hatchway pit where it reverses direction and runs to a securing means 50 on the bottom of car 11. In the bight of tape 45 thus formed a tensioning means is suspended. This tensioning means comprises a weight 51 depending from the pivot of a sheave 52 which engages tape 45. The tensioning means may be provided with a guide frame if desired. Any desired drive connection between the drum 47 and the selector machine 71 may be employed.

15 A tape drive is also employed to operate a selector machine 72 for the upper car 12. This drive comprises two tapes 53 and 54, each having one end fixed to a double sheave drum 55 located at approximately the same level as the lower hoisting machine 15 for the upper car 12. Tapes 53 and 54 are oppositely wound on drum 55 so that as tape 53 is unwound from the drum 55 by the downward motion of car 12, the drum 55 is rotated 20 in a counterclockwise direction as viewed in Figure 1 and tape 54 is wound on drum 55. Tape 53 runs directly down from drum 55 to a securing means 57 fixed to the top of the car 12. Tape 54 leads from the opposite side of drum 55, engages an idler sheave 56 arranged to guide the tape to a point outside the travel of both cars, runs directly downward along the side of the hatchway to a point near the bottom thereof where it 25 reverses, runs around a sheave 58 having a weight 59 suspended therefrom and directly up the hatchway to a securing bracket 60 fixed to the bottom of car 12. Sheave 58 is disposed at right angles to sheave 55 so as 30 to bring both vertical strands of tape 54 along the side wall of hatchway 10. The strand of tape 54 between the sheaves 55 and 58 is twisted a quarter turn. Sheave 58 and its weight 59 are guided by a frame 61 which 35 is secured to the hatchway wall and engages slotted portions of said weight. This guide frame permits only vertical movement of the weight. A similar guide frame may be provided for weight 51 and sheave 52 if desired.

40 In certain installations it may be found desirable to avoid using tensioning means and guide frames in the pit of the hatchway. To this end tapes 45 and 54 are eliminated altogether and spring or motor 45 actuated rewind mechanisms are connected to the shafts of drums 47 and 55 to put tapes 46 and 53 under tension.

45 It may be desirable to arrange the selector machines 71 and 72 at the same level. This 50 level may be approximately the same level as that occupied by either hoisting machine or an intermediate level between the hoisting machines. Arranging the selector machines at or nearly the same level facilitates their 55 interconnection by mechanical or electrical

means so that each selector machine may control or be responsive to certain functions of the other. Thus, the selector machines may control each car in accordance with the relative position and movement of the other car 70 in the hatchway in addition to the control usually effected by the selector machines. To this end selector machine 72 may be placed at the same level with machine 71 as indicated by the dotted line construction at 75 the top of Figure 2. To avoid an additional drive connection between the drum 55 and selector machine 72 this drum may be disposed at the upper hoisting machine level. It is obvious that the two selector machines, 80 together with their driving drums 55 and 47, may be placed at the lower hoisting machine level or at an intermediate level between the hoisting machines if desired.

85 The application of two elevators in one hatchway is materially limited if the lower car can travel only a part of the distance of the upper car. In order that the lower car may travel practically the same distance that the upper car does, some provision must be 90 made for preventing the lower car from fouling the traveling cable of the upper car. To accomplish this, the chute 18 is provided for the traveling cable of the upper car 12. This chute is arranged between counterweights 16 and 17 and fastened to the back wall of the hatchway. In order to get sufficient clearance for the chute it is necessary to construct very narrow counterweights. 95 In order to supply these counterweights with safety devices, as is sometimes required, it becomes necessary to place one safety device above the other instead of in the same horizontal line, which is their usual arrangement. Even though the counterweights are 100 made as narrow as possible, in some installations there will not be sufficient room to provide a chute so wide that the traveling cables can run up and down in this chute without rubbing its walls.

105 In order to make it possible to run the traveling cables of the upper car 12 in a comparatively narrow chute, without running the risk of having the cables tangled up with each other, these cables, designated 62, are clamped or tied together with cleats 63 in such a manner that the traveling cable as a whole takes the form of a belt. These cleats extend beyond the cables and are placed sufficiently close together to provide the rubbing and guiding surfaces so that the traveling cables themselves can not come in contact with the chute 18. Other means may be provided for the same purpose but the cleat arrangement affords a very simple and effective means of accomplishing the desired result.

110 One terminal of the traveling cables is 115 at a junction 64 arranged at the approximate center of the vertical travel of the up- 120

per car 12 and secured to the side wall of the chute 18 to suspend the traveling cable from a point within the chute remote from a central slot 65 which extends throughout 5 the length of the chute. The other terminal of the traveling cable is at a junction on the bottom of the elevator car 12. This end of the traveling cable is supported from the elevator car in such a way as to cause the 10 individual cables 62 to depend into the chute at the opposite side from the junction 64. The supporting means for this end of the traveling cable preferably consists in a 15 plate member 67 having its upper edge secured flush with the bottom surface of the elevator car floor by a right angle bracket or other suitable means. Support plate 67 has two oppositely directed right angle bends therein to enable it to extend through 20 slot 65 of chute 18 then along the front wall of the chute and thence along the side wall. Cables 62 are secured to the side of 25 plate 67 by straps or other suitable fasteners and depend from the end portion of the plate 67 adjacent the side wall of the chute.

The traveling cable in the form of a belt is rather flexible in the direction along the hatchway back wall but rather inflexible toward and away from this wall. The flexibility in the first mentioned direction enables the use of a narrow chute and the inflexibility in the other direction tends to prevent any depending portion of the cable 30 from emerging from the slot 65. The cleats on the traveling cable also aid in keeping it in the chute. If desired these cleats may be made of sufficient size to absolutely preclude their passage through the slot.

The traveling cable for the lower car designated 68 depends from a junction 69 fixed to the bottom of car 11 and a second junction 70 fixed to the side wall of the hatchway at the approximate vertical center thereof and adjacent the front of the hatchway. This traveling cable may also be provided with a guard chute if desired.

With the above described arrangements of the traveling cables, the lower car can be made to serve the same number of floors as 50 the upper car, and can get just as close to the upper car at any point in its travel as is desired.

In general, the lower car 11 uses the subway or lower ground floor as its lower terminal and runs express to the group of floors it serves. The upper car uses the street level or upper ground floor as its lower terminal and runs express to a group of floors located above those served by the lower car. For efficient operation the round trip time of the cars should be the same. The longer express run of the upper car takes a little longer time, but in tall buildings in which the elevators have long express runs at high speeds the difference in

time is but a very small fraction of the total round trip time. The time consumed by the elevator cars while discharging and taking on passengers at floors, and while starting and stopping at these floors constitutes the chief part of the elapsed time of a round trip. To compensate for the slight difference in time used by the express runs of the two cars the number of floors served by the upper car may be made slightly less than 70 the number served by the lower car. 75

The upper car may be dispatched from the lower terminal slightly before the lower car but preferably both leave the bottom terminals simultaneously and are so interlocked that they can leave only in this manner. Both cars run together until the lower car reaches the floors it serves, the top car continuing on at express speed to the group of floors it is to serve. Each car 80 serves its assigned group of floors traveling in the up direction to the last floor to be served and reverses making the necessary stops in the down direction at floors in its assigned group and then runs express to its 85 bottom terminal. Interlocks may be provided to prevent the cars from both traveling toward each other or from both traveling toward each other at high speed, as desired. Interlocks may also be provided to 90 prevent each car from approaching the other at high speed when the cars are separated by certain predetermined distances.

For the regular running operation of the cars the two selector machines may be mechanically or electrically interconnected to effect the interlocking functions. To this end the selector machines of the two cars may be arranged at a common level preferably at an intermediate level between the 100 two hoisting machines, as previously described.

Additional safety devices may be provided having parts extending from one or both cars toward the other for modifying 110 the operation of either or both cars when the cars are within predetermined distances of each other. The operation of these safety devices may be modified at the bottom 115 stopping zone of the cars to permit both to reach their terminals, or at other points in the hatchway to permit the two cars to make their express runs in the downward direction in the same relative positions as in the upward express runs. Both cars may be provided with car position indicators to show the location of both cars as an aid to the car operatives in controlling the operations of 120 their cars according to the relative positions of both cars in the hatchway.

As many changes could be made in the above construction and many apparently widely different embodiments of this invention could be made without departing from the scope thereof, it is intended that all mat- 125

ter contained in the above description or shown in the accompanying drawings shall be interpreted as illustrative and not in a limiting sense.

5. What is claimed is:

1. In an elevator installation; a hatchway; an elevator car adapted to travel up and down the hatchway; a traveling cable for the car; means securing the traveling cable at one end to the car and at the other end to the wall of the hatchway; a vertical chute along the hatchway within which said traveling cable is contained, said chute having a vertical opening throughout its length 10 through which opening extends the means securing the car end of said traveling cable; and means attached to said traveling cable and cooperating with the edges of the vertical opening in said chute for preventing 15 egress from said chute of any portion of said traveling cable.

2. In an elevator installation, a hatchway, an elevator car adapted to travel up and down in said hatchway, traveling cables depending from said car and a wall of the 25 hatchway, a chute for said traveling cables for preventing said cables from fouling objects in the hatchway, and means arranged on said cables to prevent the cables from 30 rubbing the chute.

3. In an elevator installation, a hatchway, an elevator car adapted to travel up and down said hatchway, traveling cables depending from said car and a wall of said 35 hatchway, a chute for said traveling cables for preventing said cables from fouling objects in the hatchway, and means for securing said cables together in the form of a belt and for preventing the cables from 40 rubbing the chute.

4. In an elevator installation, a hatchway, an elevator car adapted to travel up and down in said hatchway, traveling cables communicating between the elevator car and 45 a junction in the hatchway, a chute for said cables disposed adjacent the elevator car and parallel with the hatchway, said chute having a central opening extending throughout its length, a support for the car end of 50 the cables entering into said chute through said opening, and means secured to said cables for preventing any portion of said cables for swinging out of said chute through said opening.

5. In an elevator installation, a hatchway, an elevator car adapted to travel up and down in said hatchway, traveling cables depending from said car and a wall of said hatchway, a chute for said traveling cables 55 disposed along the wall of said hatchway, said chute having a vertical slot therein, the car end of said cables extending into said chute through said slot and said slot extending throughout the path of travel of 60 said car end of the cables, and cleats at-

tached at intervals to said cables to clamp them together in the form of a belt, to prevent any portion of the cables from swinging out of the slot and to prevent the cables from rubbing the sides of the chute. 70

6. In an elevator installation, a hatchway, two elevator cars therein and arranged one above the other, two hoisting machines arranged one at a level above that of the other at the top of the hatchway, two counterweights arranged adjacent and parallel to the back wall of the hatchway, a traveling cable chute arranged between the counterweights, and two sets of hoisting cables for the cars, one set running from the lower car 75 up to the upper machine and thence down to one counterweight, the other set running from the upper car up to the lower machine and thence down to the other counterweight. 80

7. In an elevator installation, a hatchway, a pair of guide rails secured to the side walls of the hatchway, two elevator cars mounted on said rails one above the other, two hoisting machines for said cars arranged one at a level above that of the other at 85 the top of the hatchway, a hoisting sheave on each of said machines, two counterweights one for each car arranged adjacent and parallel to the back wall of the hatchway, hoisting roping for the upper car passing over the hoisting sheave of the lower hoisting machine and connected at one end to the upper car and at the other end to the upper car counterweight, the lower hoisting machine being skewed at an angle with respect to the back wall of the hatchway so that its hoisting sheave lies in a plane which includes the center of gravity of the upper car and the center of gravity of the upper 90 car counterweight, hoisting roping for the lower car passing over the hoisting sheave on the upper hoisting machine and connected at one end to the lower car counterweight and at the other end to the lower car at two points of attachment oppositely disposed with respect to the approximate center of 95 gravity of the lower car, one point of attachment being between a guide rail and the back wall of the hatchway and the other point of attachment being between the other guide rail and the front of the hatchway, and sheaves for guiding one half of the hoisting roping for the lower car from a point above said one point of attachment across the top 100 of the hatchway to a point above the other point of attachment, the upper hoisting machine being skewed at an angle with respect to the back wall of the hatchway so that its hoisting sheave lies in a plane which includes the center of gravity of the lower car counterweight and the said one point of attachment to the lower car. 105

8. In an elevator installation, a hatchway, a pair of guide rails secured to the side walls of the hatchway, two elevator cars mounted 110

115

120

125

130

on said rails one above the other, two hoisting machines for said cars arranged one at a level above that of the other at the top of the hatchway, a hoisting sheave on each of said machines, two counterweights one for each car arranged adjacent and parallel to the back wall of the hatchway, a traveling cable for each car, each traveling cable secured at one end to its car and at the other end to a point in the hatchway, a chute arranged between the counterweights for confining the traveling cable for the upper car, hoisting roping for the upper car passing over the hoisting sheave of the lower hoisting machine and connected at one end to the upper car and at the other end to the upper car counterweight, the lower hoisting machine being skewed at an angle with respect to the back wall of the hatchway so that its hoisting sheave lies in a plane which includes the center of gravity of the upper car and the center of gravity of the upper car counterweight, hoisting roping for the lower car passing over the hoisting sheave on the upper hoisting machine and connected at one end to the lower car counterweight and at the other end to the lower car at two points of attachment oppositely disposed with respect to the approximate center of gravity of the lower car, one point of attachment being between a guide rail and the back wall of the hatchway and the other point of attachment being between the other guide rail and the front of the hatchway, sheaves for guiding one half of the hoisting roping for the lower car from a point above said one point of attachment across the top of the hatchway to a point above the other point of attachment, the upper hoisting machine being skewed at an angle with respect to the back wall of the hatchway so that its hoisting sheave lies in a plane which includes the center of gravity of the lower car counterweight and the said one point of attachment to the lower car.

9. In an elevator installation, a hatchway, a pair of guide rails secured to the side walls of the hatchway, two elevator cars mounted on said rails one above the other, two hoisting machines for said cars arranged one at a level above that of the other at the top of the hatchway, a hoisting sheave on each of said machines, two counterweights one for each car arranged adjacent and parallel to the back wall of the hatchway, hoisting roping for the upper car passing over the hoisting sheave of the lower hoisting machine and connected at one end to the upper car and at the other end to the upper car counterweight, the lower hoisting machine being skewed at an angle with respect to the back wall of the hatchway so that its hoisting sheave lies in a plane which includes the center of gravity of the upper car and the center of gravity of the upper car counter-

weight, hoisting roping for the lower car passing over the hoisting sheave on the upper hoisting machine and connected at one end to the lower car counterweight and at the other end to the lower car at two points of attachment oppositely disposed with respect to the approximate center of gravity of the lower car, one point of attachment being between a guide rail and the back wall of the hatchway and the other point of attachment being between the other guide rail and the front of the hatchway, sheaves for guiding one half of the hoisting roping for the lower car from a point above said one point of attachment across the top of the hatchway to a point above the other point of attachment, the upper hoisting machine being skewed at an angle with respect to the back wall of the hatchway so that its hoisting sheave lies in a plane which includes the center of gravity of the lower car counterweight and the said one point of attachment to the lower car, compensating roping for the upper car, tensioning sheaves for said compensating roping, said compensating roping being connected at one end to the upper car at two points of attachment oppositely disposed with respect to the approximate center of gravity of the upper car and on the opposite sides of the guide rails with respect to the points of attachment of the hoisting cables for the lower car and at the other end to said upper car counterweight, said compensating roping extending downwardly from the upper car around the tensioning sheaves and upwardly to the upper car counterweight, compensating roping for the lower car, and a tensioning sheave for the compensating roping for the lower car, said lower car compensating roping being connected at one end to the lower car and extending downwardly from the car around the tensioning sheave and upwardly to the lower car counterweight, the other end of said last named compensating roping being attached to the lower car counterweight.

10. In an elevator installation, a hatchway, two elevator cars therein and arranged one above the other, a hoisting machine for each car arranged at the top of the hatchway, a hoisting sheave on each machine, a counterweight for each car arranged adjacent and parallel to the back wall of the hatchway, hoisting roping for the upper car passing over the hoisting sheave of one machine and connected at one end to the upper car at the top thereof and at the other end to the upper car counterweight, and hoisting roping for the lower car passing over the hoisting sheave of the other machine and connected at one end to the lower car at the bottom thereof and at the other end to the other counterweight.

11. In an elevator installation, a hatch-

way, two elevator cars therein and arranged one above the other, a hoisting machine for each car arranged at the top of the hatch-way, a hoisting sheave on each machine, a 5 counterweight for each car arranged adjacent and parallel to the back wall of the hatch-way, hoisting roping for the upper car passing over the hoisting sheave of one machine and connected at one end to the upper car 10 at the top thereof and at the other end to the upper car counterweight, hoisting roping for the lower car passing over the hoisting sheave of the other machine and connected at one end to the lower car at the 15 bottom thereof and at the other end to the other counterweight, compensating roping for the upper car connected at one end to the upper car at the top thereof and at the other end to the upper car counterweight, 20 and compensating roping for the lower car connected at one end to the lower car at the bottom thereof and at the other end to the lower car counterweight.

In testimony whereof, I have signed my 25 name to this specification.

DAVID LEONARD LINDQUIST.
